UNITED STATES PATENT OFFICE.

ALBERT J. RUST, OF WILLIAMS, CALIFORNIA.

ROTARY PUMP.

1,050,300.

Specification of Letters Patent.

Patented Jan. 14, 1913.

Application filed July 24, 1911. Serial No. 640,179.

To all whom it may concern:

Be it known that I, ALBERT J. RUST, a citizen of the United States, residing at Williams, in the county of Colusa and State 5 of California, have invented new and useful Improvements in Rotary Pumps, of which the following is a specification.

My invention relates more particularly to rotary pumps for compressing air but may 10 be used for pumping other gases or fluids and the object thereof is to provide a pump of simple construction and great efficiency and in which ample provision is made for taking up any wear on the parts.

15 A further object is to provide means to circulate a small quantity of oil through the pumping chamber whereby a film of oil is maintained on the contact surfaces of moving parts and also on the parts with which 20 the moving parts contact whereby such film of oil forms a frictionless packing thereby making the contacts airtight.

I accomplish this object by means of the mechanism described herein and illustrated 25 in the accompanying drawings, in which:—

Figure 1 is a section on the line 1—1 of Fig. 2. Fig. 2 is a section on the line 2—2 of Fig. 1. Fig. 3 is a section on the line 3—3 of Fig. 1. Fig. 4 is a section on the 30 line 4—4 of Fig. 3. Fig. 5 are detail views of the piston blades showing an edge and a side view respectively with one blade in section. Fig. 6 are detail views of the packing of the piston blades, being an edge and 35 a side view thereof.

In the drawings I have illustrated my machine as designed for pumping air and will describe it as applied to that use. I have illustrated the pump as designed to be attached to a vertical surface but it is equally 40 adapted for attachment to any other surface, but if attached to any other surface the position of the parts shown in the drawings must be preserved to produce the best results 45 in the circulation of the oil. If used for pumping liquids the oil circulating feature can be omitted and the position in which the pump is placed is then immaterial.

In the drawings 10 is the casing in which 50 is formed a cylindrical shaped pumping chamber 11. At one side of the pumping chamber, which as illustrated is the right hand side, when the pump is positioned for use is the oil supply chamber 12. These 55 chambers are connected by a channel 13 which when the pump is positioned for use

leads out of the oil chamber near the top thereof as best shown in Fig. 2.

Mounted in the pumping chamber and eccentric to the center thereof is the pumping piston 14 which is circular and preferably hollow. On one side of the piston and connected thereto, being preferably cast integral therewith, is an operating shaft 15 which projects through a boss 16 on the side 60 of the chamber casing. Adjacent the pumping chamber the operating shaft tapers for a short distance, say about $\frac{1}{4}$ its length as best shown in Fig. 1. The remainder of the shaft within the boss is preferably of 65 the same diameter. Exterior the boss the shaft is preferably reduced in diameter and on this reduced portion is mounted the driving pulley 17 to which power is applied to rotate the shaft. 75

Surrounding the piston shaft within the boss is the shaft adjuster 18. The shaft is positioned eccentric to the center of the adjuster as best shown in Fig. 3. The inner end of the bore of the adjuster has a taper 80 to fit that portion of the shaft next the piston. The diameter of the outer end of the bore of the adjuster is uniform and the intermediate portion tapers inwardly as best shown in Fig. 1. These configurations permit of the wear being taken up. The upper portion of the adjuster is provided with a multilated worm gear 19 which meshes with a worm 20 on shaft 21, which shaft is mounted in the casing as best shown in Fig. 90 3. In the end of this shaft is a slit 22 in which is received the end of a screw driver or other tool to rotate the shaft when desired. A lock-nut 23 locks the shaft in its adjusted position. 95

Surrounding the piston shaft within the adjuster is an adjusting cone-shaped washer 24 which is adjusted by means of nut 25 which is screwed on the shaft. A lock nut 26 holds nut 25 in its adjusted position. The piston is provided with four radial slots 27 in which are mounted piston blades 28. The opposed piston blades are connected by connecting rods or bolts 29 which permit the blades to contract 100 to the smallest diameter. On these bolts are mounted springs 30 which hold the blades in contact with the periphery of the pumping chamber. In the outer ends of the blades are mounted contact wearing rockers 31 which are circular in cross section with an arc cut off one side for the wearing sur- 110

face, which contacts with the perimeter of the pumping chamber. The ends of the blades have circular shaped grooves 32 into which these rockers are received.

5 In one end of the pumping chamber is the air inlet port 33 which is preferably triangular shaped as shown in Figs. 2 and 3. On the opposite side of the pumping chamber is the discharge port 34 from which the 10 air is led to its place of storage or use. Between these ports and at the bottom of the chamber the piston touches the perimeter of the pumping chamber. A relief groove 35 in the casing extends from the edge of 15 this contact to a point above the bottom of the inlet port so that as the piston blades are moved a vacuum is not produced behind them. The inlet port is inclosed on its outer side by a horn shaped casing 36 open 20 at the top. This casing prevents any oil escaping from the pump. Extending from the bottom of the oil chamber is the feed pipe 37 which passes out of the oil chamber through the top thereof and runs to and enters valve chamber 38 best shown in Fig. 1. 25 A valve 39 controls the flow of oil out of the valve chamber. From the valve chamber the oil flows through port 40 and drops through the sight feed chamber 41 and 30 passes through an L-shaped supply channel 42 to the piston shaft.

From the piston shaft the oil passes through a port 43 in the adjuster and into an L-shaped exhaust channel 44 which opens 35 into the air inlet and is carried by the air into the pumping chamber where it is carried around by the piston blades, thereby lubricating the piston and the walls of the pumping chamber, on all of which parts it 40 is deposited in a thin film which makes a frictionless packing between the moving parts. All surplus oil is thrown out into the discharge passage from which it drains back into the oil chamber. Should any oil work 45 outwardly on the operating shaft or on the outside of the adjuster it will be prevented from escaping by the packing gland 45 in which gland is located a shaft packing gland 46. There is a small space between 50 packing gland 45 and the end of the adjuster through which the oil can drop. A channel 47 in the adjuster connects with channel 44. A port 48 closed by plug 49 provides means to drain the oil out of the 55 oil chamber when desired. A sight chamber 50 is connected to the oil chamber to enable the operator to know how much oil is in the chamber. The oil is fed into the pump through the air inlet.

60 To provide for wear on the piston blades I have provided grooves 51 in the piston. In these grooves are packing strips 52 which are held in contact with the blades by springs 53 thereby keeping the joint between 65 the blade and the piston always tight. The

end of the pumping chamber opposite the piston shaft is closed by a head 54 which can be screwed farther in to take up any wear on the ends of the chamber. It is held positioned by lock nut 55. As the adjuster 70 is revolvable in the boss of the pumping chamber, and as the operating shaft which carries the pumping piston is mounted in the adjuster eccentric to its center it is obvious that the rotation of the adjuster will 75 carry the pumping piston toward or away from the perimeter of the pumping chamber thereby enabling the piston to be adjusted to take up the wear. By this construction it will be observed that a circulation of oil 80 is constantly maintained through the pump which not only keeps all the parts perfectly lubricated but also forms a frictionless packing between the walls of the pumping chamber and the piston and its blades. 85

Having described my invention, what I claim is:

1. The combination with a fluid compression pump, of an oil reservoir connected at its top with the compression chamber, and an oil way leading from the bottom of said reservoir through the bearings of the machine and terminating in the suction of the pump. 90

2. A rotary pump comprising a casing, 95 having a cylindrical pumping chamber therein with an inlet and an outlet port adjacent to each other; a circular piston mounted in said chamber eccentric to the center thereof and contacting with the perimeter 100 between said ports, said piston having a plurality of radial slots therein, said slots being two or a multiple thereof; piston blades slidably mounted in said slots, said blades having circular grooves in the outer 105 ends thereof and holes in the opposing faces of each pair; contact rockers mounted in the grooves in the ends of said blades; connecting rods connecting opposed blades, said rods entering the holes in said blades; 110 springs on said rods; means to adjust the end wear on the pumping chamber and the wear of the piston blades which contact therewith; an oil chamber connected to the pumping chamber near the outlet 115 port; a pipe leading from the bottom of said oil chamber and carrying oil to a valve chamber; a valve chamber, a valve in said chamber; a sight feed chamber connected to the valve chamber, a channel leading to 120 the operating shaft; and an exhaust channel leading from the operating shaft to the suction of the pump. 125

3. In a rotary pump a casing having a cylindrical pumping chamber said chamber having ports at a distance apart, one being the inlet and the other the outlet port; a boss on one side of said casing; an adjuster concentrically and revolvably mounted in said boss; means to rotate said adjuster in 130

said boss; a circular piston having operating blades and mounted in the chamber to contact with the perimeter of the chamber between said ports; an operating shaft secured to said piston and projecting through the said boss and through the adjuster eccentrically to the center of the adjuster.

In witness that I claim the foregoing I have hereunto subscribed my name this 14th day of July, 1911.

ALBERT J. RUST.
